No. 15,066

June 17, 1884

UNITED STATES PATENT OFFICE.

PAUL GROEBER, OF NEW YORK, N. Y.

DESIGN FOR WALL-PAPER.

SPECIFICATION forming part of Design No. 15,066, dated June 17, 1884.

Application filed April 11, 1884. Term of patent 3½ years.

To all whom it may concern:

Be it known that I, PAUL GROEBER, a citizen of the United States, residing in the city of New York, county and state of New York, 5 have invented and produced a new and original Design for a Wall or Ceiling Covering, which is especially intended as a wall-hanging, of which the following is a specification.

The drawing represents a front plan view 10 of the design.

The design consists of three squares of equal size, but of different pattern, in different relative positions. The motive of the design is to represent the appearance of tiles. Each 15 tile consists of a square having within it a circle, *a*, the circumference of which reaches the four sides of the square. The angular space at each corner of the square is occupied by a section of a circle, *b*, the center of the circle 20 being located at the extreme point of the corner, radiating from which are lines *c*, having a minute knot at the apex. The lines are united by curved lines at their outer ends, giving the whole the appearance of a webbed 25 wing.

So far this description is common to all the tiles. The interiors of the circles are, however, unlike. The several styles are marked, respectively, 1, 2, and 3. No. 1 has for its center a star, *d*, consisting of a rosette surrounded 30 by ten leaflets and two circles. This is followed by a floral wreath and circular band, *e*. Radiating from the last is a series of projections, *f*, with rounded tops, each having at

its base a leaf. A fringed circle, *g*, surrounds 35 the projection. Lastly, a wreath of flowers, scrolls, and leaflets, *h*, forms the outer border, reaching the circumference of the outer circle. No. 2 has for its center a beaded button, *i*, surrounded by a circular band. Radiating 40 from this are sixteen sprays of leaves, *k*, enclosed by a luted circular border, *l*. Radiating from the last is a circular border of flaming tongues, *m*, which overlap. The interior decoration of the circle is completed by 45 a circular band of bars placed at regular distances. No. 3 has for its center a rosette, *n*, with eight leaflets bounded by a circle, radiating from which spring volutes and leaves. The circle is next divided into eight divisions 50 by ladder-shaped ornamental figures *o*, each division being ornamented with sprays of leaves, rosettes, scrolls, and palmated leaves, which are placed in alternate panels. A border of lotus-leaves completes the design to the 55 circumference of the circle. The above-described squares are shown with dissimilar squares immediately in contact.

I claim—

The design herein shown and described, consisting of the combination of squares embodying substantially the elements shown and described in the squares herein designated 1, 2, and 3. 60

PAUL GROEBER.
